UNITED STATES PATENT OFFICE.

JAMES F. NEWTON, OF PHILADELPHIA, PENNSYLVANIA, ASSIGNOR TO PRIMROSE TAPESTRY CO., INC., OF PHILADELPHIA, PENNSYLVANIA.

DESIGN FOR A VALANCE OR SIMILAR ARTICLE.

Application filed October 11, 1927. Serial No. 23,713. Term of patent 7 years.

To all whom it may concern:

Be it known that I, JAMES F. NEWTON, a citizen of the United States, residing at Philadelphia, in the county of Philadelphia and State of Pennsylvania, have invented a new, original, and ornamental Design for Valance or Similar Article, of which the following is a specification, reference being had to the accompanying drawing, forming a part thereof.

The figure is a face view of a portion of a valance or similar article, showing my new design.

I claim:

The ornamental design for a valance or similar article, as shown.

JAMES F. NEWTON.
